Des. 227,756
Patented July 17, 1973

227,756

LIFT TRUCK BODY

William O. Smart, Peoria, and Kenneth Roncketti, Chicago, Ill., and Barry L. Zauss, Venice Beach, Calif., assignors to Towmotor Corporation, Cleveland, Ohio

Filed May 18, 1971, Ser. No. 145,120

Term of patent 14 years

Int. Cl. D12—09

U.S. Cl. D14—3 A

—1—

FIG. 2 - 2 -

H-5 - 3 -

H-5 - 4 -

HG-5-

FIG - 6 -

FIG. 1 is a perspective view taken forwardly and to one side of a lift truck body embodying our new design;

FIG. 2 is a perspective view taken rearwardly and to one side of the same;

FIG. 3 is a plan view of the same;

FIG. 4 is a right side elevational view of the same;

FIG. 5 is a rear elevational view of the same; and

FIG. 6 is a left side elevational view of the same.

We claim:

The ornamental design for a lift truck body, substantially as shown and described.
